UNITED STATES PATENT OFFICE.

CHARLES A. RIVARD, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

ENGRAVING-MACHINE.

1,285,795.

Specification of Letters Patent. Patented Nov. 26, 1918.

Application filed February 13, 1918. Serial No. 217,010.

To all whom it may concern:

Be it known that I, CHARLES A. RIVARD, a citizen of the United States, residing at Providence, in the county of Providence and State of Rhode Island, have invented a new and useful Improvement in Engraving-Machines, of which the following is a specification.

This invention relates to certain new and useful improvements in engraving machines, and more particularly to that type of engraving machine set forth in my application for patent Serial No. 190028, filed September 6, 1917.

15 In my former construction I provided a machine for engraving or cutting patterns on rolls, copying a pattern from another roll. The present invention seeks to provide a machine having a stylus and cutter for operating on a cylindrical member or roll and a disk, one of which two last named elements bears the pattern for reproduction upon the other element. Thus, should the pattern be carried on the roll, the reproduction on the disk will be more or less annular in formation.

20 In the drawings—

Figure 1 is a top plan view of an engraving machine constructed in accordance with 30 the present invention.

Fig. 2 is a fragmentary front elevation thereof.

Fig. 3 is a transverse section on line 3—3 of Fig. 2.

35 Fig. 4 is a fragmentary top plan view of a modified arrangement of the parts of the machine.

Referring to corresponding parts by like characters of reference, the numeral 1 designates the body of the machine provided with spaced pairs of bearings 2 in which are journaled the shafts 3 and 4, the pattern shaft 3 being extended to carry a drive gear 5 which derives its source of power from a suitable 45 transmission. The work operating shaft 4 carries a fixed gear 7 that is interposed between a pair of sliding gears 8 for selective mesh therewith. Said gears 8 are carried on a third shaft 9 having driving connection 50 with shaft 3 through beveled gearing 10, thereby providing positive drive for each shaft 3 and 4, the ratio between the connecting gears being such as to give the shafts similar rotary movement.

55 The stylus and cutter carrying beam 11 is

pivotedly supported at one end by the fulcrum plate 12 for relative horizontal movement toward and from the work and pattern, and for vertical movements said fulcrum plate is carried by a shaft 13 which is journaled in bearings 14 on the frame 1. Substantially midway between its ends, the beam 11 is provided with a roller bearing 15 that rides in and out on the underlying and outwardly extending bracket arm 16 which may 65 be adjusted vertically through the medium of a screw 17.

Adjustably mounted on the beam 11 is a tracer 18, opposite the pattern shaft 3, and a milling cutter 19, opposite the work shaft 4, 70 said cutter being rotated by means of an endless belt 20 passing about the pulley 21, on the cutter shaft and the several idlers 22 and take-up 23.

As in my former construction, a beveled 75 gear 24 is fixed on the forward end of the pattern shaft 3 for meshing with and driving the beveled gear 25 which is fixedly carried on the lower end of a vertical shaft 26. This shaft is journaled in the overhanging 80 bearing 27 of a bracket 28 that has spaced supporting webs for seating on the bearings 2 where it is secured by suitable fastenings 29.

A bracket 30 is secured to the front of the 85 frame and beneath the overhanging bracket 28 by fastenings 31, and through said bracket 30 is passed a vertical centering pin 32 for supporting the pattern roll 33.

The work disk 34 is secured within a chuck 90 35 which is carried on the forward end of shaft 4 so as to directly oppose the cutter.

In operation, the tracer or stylus, in its movements over the pattern roll, imparts an in and out motion to the beam which accordingly controls the cut of the milling cutter on the work disk, reproducing the pattern on the latter in a manner, so to speak, as if the periphery of the roll was laid out flat and then bent into annular dish-like form. 100 Owing to the relative spacing of the cutter and stylus from the pivotal mounting of the beam 11, the reproduction will in this instance be on a reduced scale, but by simply reversing the position of the pattern roll, the 105 reproduction will be enlarged relative to the pattern.

This arrangement is illustrated in Fig. 4, the work disk 34 being secured in the chuck 35 that is carried by the shaft 3. Shaft 4 110

is provided with a beveled gear 24' for driving a similar gear 25' which is carried on the lower end of vertical shaft 26', the pattern roll being secured or mounted in a similar manner to that shown in Fig. 2. The overhanging bracket 28' is also provided for supporting the vertical shaft 26' in its bearing 27'.

While the roll, in the present instance has been designated the pattern carrying element, it is quite obvious that the pattern could be prepared on the disk for reproduction on a work roll or cylinder.

Having thus described my invention, what I claim as new and desire to secure by Letters Patent is—

1. In an engraving machine, a cutter, a tracer, a flat disk element for one of the aforesaid members to operate on, and a cylindrical element for the other of said members to operate on, one of said elements bearing the pattern, means operatively connecting the cutter and tracer, and means for rotating the elements about their axes which are arranged at right angles to each other.
2. In an engraving machine, a universally mounted rigid beam, a cutter and a tracer carried thereon, a pattern roll rotatably mounted for coöperation with the tracer, and a rotatably mounted disk arranged to be operated upon by the cutter.
3. In an engraving machine, a rigid beam mounted for in and out motion, a tracer and a cutter carried thereby at spaced points, and means for rotatably supporting pattern and work elements adjacent the tracer and cutter, one of said elements being a disk and the other a roll.
4. In an engraving machine, a rigid beam pivoted at one end for in and out movement, a tracer and cutter carried thereby at spaced points, and means for rotatably supporting pattern and work elements for operation thereon by the tracer and cutter and with their axes arranged at right angles to each other.

5. In an engraving machine, horizontally disposed pattern and work operating shafts, a disk holding chuck fixed to the end of one shaft, a bracket overlying the other shaft, a vertical shaft journaled in the bracket, gearing connecting the vertical shaft and the second horizontal shaft, a centering pin arranged beneath the vertical shaft, a roll vertically supported by the pin and its overlying vertical shaft, a disk carried by the chuck, a beam mounted for in and out movement toward and away from the roll and disk elements, and a tracer and cutter carried by the beam for operating on the roll and disk elements, one of which latter carries the pattern.

6. In an engraving machine, a pair of parallel related shafts, means for rotating the same, means for securing a disk to one shaft for rotation about the axis of the shaft, means for mounting a roll to rotate about an axis at right angles to the axis of the second shaft, a cutter and tracer for operating on the disk and roll, and means supporting the cutter and tracer for movement.

7. In an engraving machine, pattern and work operating shafts arranged to rotate at right angles to each other, a disk-carrying clutch fixed to an end of one shaft, roll-securing means carried by the other shaft for holding and rotating a roll at right angles to the first shaft, a single beam pivoted at one end whereby its opposite end portion may move toward and from said clutch and means, and a tracer and cutter mounted on the beam at spaced points to operate on the roll and disk elements.

In testimony whereof I have signed my name to this specification in the presence of two subscribing witnesses.

CHARLES A. RIVARD.
